[57] **CLAIM**

The ornamental design for a console suitable for accommodating computers and terminals, as shown and described.

DESCRIPTION

FIG. 1 is a front elevation view of a console suitable for accommodating computers and terminals showing my new design;

FIG. 2 is a front and side perspective thereof;

FIG. 3 is an enlarged fragmented view of the upper front portion thereof shown for clarity of illustration only; and, FIG. 4 is a side view thereof.

The undisclosed side view is identical to the side shown and the rear and bottom views are not a part of the claimed design.
